(57) **CLAIM**

The ornamental design for a nail with a head having an inwardly curved top surface, as shown and described.

DESCRIPTION

This application is related to the following commonly owned co-pending patent application: U.S. application Ser. No. 16/447,408, entitled “Nail with a Head Having an Inwardly Curved Top Surface”.

FIG. 1 is a top-perspective view of the nail with a head having an inwardly curved top surface of our new design. FIG. 2 is a front-side-elevational view of the nail with a head having an inwardly curved top surface of FIG. 1, the back-side-, right-side-, and left-side-elevational views being identical thereto.

FIG. 3 is a top-plan view of the nail with a head having an inwardly curved top surface of FIG. 1.

FIG. 4 is a bottom-plan view of the nail with a head having an inwardly curved top surface of FIG. 1; and,

FIG. 5 is a cross-sectional-front-side-elevational view of the nail with a head having an inwardly curved top surface of FIG. 1 taken along line 5-5 of FIG. 3.

The broken lines in the drawings illustrate portions of the nail with a head having an inwardly curved top surface and form no part of the claimed design.

The dot-dot-dash broken line rendered in FIG. 5 defines the bounds of the claim and form no part thereof.
